UNITED STATES PATENT OFFICE.

JAMES B. VAN DEREN, OF KINGFISHER COUNTY, OKLAHOMA.

AUTOMATIC WEIGHING MACHINE.

Application filed September 26, 1922. Serial No. 590,609.

My invention relates to automatic weighers employing a two compartment container and doors in controlling the discharge openings of the compartments, and among 5 the objects of my improvements are, sure and rapid operation combined with accurate weighing and a machine that will not leak or litter. With these and other objects in view, the invention consists in certain novel 10 and useful features of construction and combination of parts as hereinafter described and claimed; and in order that it may be fully understood, reference is to be had to the accompanying drawings, in 15 which:—

Figure 1 is a front elevation showing a container with portions cut away to show the working parts described;

Figure 2 shows the relation of door hinges 20 and adjacent parts to the container and the manner of flanging the side walls of the container;

Figure 3 shows one of the doors and the torsion supporting hinge body employed;

Figure 4 shows the rocker member with knife edge bearings;

Figure 5 is a side view of the last mentioned combination, and, for convenience, shows the member mounted on the part- 30 tion;

Figure 6 shows a different form of deflector with flanges at either end;

Figure 7 shows another form of deflector which may be employed;

Figure 8 shows a latch mechanism differ- 35 ent from that shown in Figure 1;

Figure 9 is a side view of the last mentioned combination, and,

Figure 10 shows a section of grooved pul- 40 ley with cable attached, which may be em- ployed in place of the rocker element shown in Figures 1, 4 and 5.

Referring to the drawings in detail, 1 indicates a container, 2 a vertical partition 45 dividing a portion of the container into two compartments 3 and 4. And 5 and 6 show lugs to pivot on knife edges 7 and 8, which knife edges are a portion of a scale yoke or beam (not shown) which rests on knife 50 edges at 9 and 10. It will thus be seen that the container is suspended from a scale beam, it being deemed unnecessary to show the entire scale beam mechanism.

11 indicates a division bar extending 55 downward from the partition, and 12 and 13 show wing doors for opening and closing

the bottoms of the compartments alter- nately. The ends of the doors are turned upward to overlap the sides of the compartments, when the doors are closed, and to 60 form a chute for directing the weighted commodity into a receiver.

The doors are hinged at 14 and 15, which 65 hinges are placed preferably, above the plane of the bottoms of the compartments respectively, when the doors are closed, and above the plane of the commodity supporting surfaces of the doors. 16 indicates an upwardly extending flange at the outer edges of the doors respectively, and 17 70 shows the lower edge of the side walls of the respective compartments carved inwardly and downwardly to near the surfaces of the doors, when closed. With the doors hinged as indicated, there is a very wide 75 opening between the edge of flange 17 and the door surfaces when the doors are open, and a substantially complete closure when the doors are closed, and the flanges present a thin edge to the door surfaces, in the clos- 80 ing movement, so that should any commodity adhere to the door surfaces the flanges will cut through it, as the doors close, without materially retarding the free movement of the doors. And flange 16 will prevent 85 any commodity that might get behind flange 17 from getting out at the sides of the compartment and will compel it to be discharged in the regular way. This com- bination is shown quite clearly as indicated 90 by numerals 15, 16 and 17 in Figure 2.

The division bar 11 permits placing the discharge openings of the compartments close together without the opening door dis- 95 charging on to the closing door, and per- mits the closed door assuming a relaxed position without material discharge. And it will be noticed that, owing to the position of the door hinges, the doors have a freeing movement in relation to the division 100 bar so that a very close joint may be made without danger of hanging in the opening movement of the doors. In fact the surfaces of the division bar may be made slightly concave without danger of the doors bind- 105 ing thereon in their opening movement.

Links 19 and 20 are pivotally connected to the doors respectively, at 19^a and 20^a, their upper ends being pivotally connected respec- 110 tively, to the respective arms of a T-shaped rocker 21, at 21^a and 22^a, which rocker is rigidly mounted on shaft 22, which shaft

is journalled on the container, it being important only, that the rocker be pivoted on surfaces bearing a fixed relation to the supporting portion of the door hinges.

5 Rigidly mounted on shaft 22 is locking lever 23, which is preferably mounted within the container, shown, which has oppositely extending arms 24 and 25, adapted to engage with gravity catches 26 and 27, 10 which, for convenience, are shown mounted on hopper 28, but may be mounted on any convenient object stationary relative to the downward and upward movement of the container in response to a scale poise. The 15 gravity catches are provided with adjusting screws 29 and 30, which normally rest on knife edges 31 and 32, said adjusting screws providing means for adjustments as between the compartments so that they will each trip 20 the latch mechanism under a like accumulation of weight. The knife edges 31 and 32 present a small surface to the adjusting screws and therefore prevent the accumulation 25 of dirt under the free end of the gravity catches which would prevent their seating the same during each weighing operation and consequently cause uneven weighing.

Pivotedly mounted on hopper 28 is an oscillating chute 33, pivoted at 33^a and having 30 a like pivot at the opposite end of the hopper (not shown), and adapted to alternately change the flow of commodity from one compartment to the other as the doors are opened and closed. Means for effecting this 35 oscillation is provided by link 34 pivotedly attached at one end to locking lever 23 at 34^a and its other end to rocking lever 35 at 36, which rocking lever is pivotedly mounted on the container at 37, and to the 40 upper arm of which is pivotedly connected link 38, the other end of said link being pivotedly connected to chute 33 at 39.

It will be noticed that by reason of the 45 pivotal connections of the links to the rocker 21 being above its pivotal mounting 22, the opening door gains in leverage as it opens while the closing door cooperatively decreases in resistance, and that after the balanced relation point is passed the opening 50 door gains a preponderance of leverage, which will insure the full opening of the door and full closing of the other door. This relation of parts also greatly reduces friction on the trip mechanism and causes a 55 very quick movement of the deflector in the early portion of its movement, in relation to the movement of the doors.

The connection of the links 19 and 20 to the doors below the plane of the door hinges, 60 relative to the supporting surfaces of the doors, and laterally nearer the vertical plane of the hinges than the free edges of the doors, gives the doors a leverage on the links and gives the pivot points of the links a 65 more pronounced movement toward the ver-

tical plane of the door hinges, as the doors open, which tends to increase the leverage of the opening door and decrease the leverage of the closing door. Thus it will be seen 70 that the doors cooperate with the rocker in giving the opening door an increasing leverage and the closing door a decreasing resistance, and, while this leverage may be obtained by the rocker and its link connections alone, it is preferable that the doors do not 75 detract from such leverage to any great extent.

By positioning the links to rocker 21 any 80 desired degree of leverage may be obtained, from the slightest to almost a complete lock, and, for all purposes in a machine of this character, it may become a lock for it can be made to sustain any load that should be placed in either compartment of the container.

As this element of leverage can be made 85 to greatly increase the operative-power efficiency of the opening door and the holding power of the open door, it is very beneficial whether the operative power of the 90 opening door is relied on for the operation of the doors and other operable elements or other power elements are employed therewith—it is positive, reliable, economical and 95 prevents strain or shaking motion being applied to the container as where extraneous power is wholly relied on.

In operation, assuming that the parts bear 100 the relation shown in Figure 1, commodity will be directed into compartment 3 until the scale poise is overbalanced, when the entire container will descend withdrawing arm 24 from engagement with gravity catch 26, when locking lever 23 will swing to the left, rocker 21 accompanying it, which will 105 permit door 12 to open and close door 13, and arm 25 of the locking lever will pass gravity catch 26 and be prevented from a return movement by engagement therewith, thus locking door 13 in closed position. In 110 the meantime the chute 33 will have changed its position and will direct the flow of commodity into compartment 4. Should the container begin to ascend before the arm has passed the gravity catch, then the catch 115 will yield upwardly permitting the free passage of the arm to locking position and then drop into place.

In Figures 4 and 5 a different form of 120 rocker bar and locking arm are shown; 40 indicates a bracket secured to the partition 2, having upwardly extending portions 41 and 42 which have a circular opening at the tops thereof as shown at 43, and the lower end of the rocker 21 has knife edges which rest in 125 said circular openings 41 and 42 respectively, as shown in Figure 5. Links 19 and 20 are attached to the respective arms of the rocker as in Figure 1. An extension arm 23^a, is made in connection with the rocker to 130

take the place of locking arm 23 of Figure 1.

The principal object of this combination is to secure a more quick action of the doors and other parts by reduction of friction by use of the knife edges as bearings for the rocker, and by placing the rocker on the partition and having the locking arm as a part thereof, the links, or other power transmitting means may be connected directly to the doors without the intervention of the shaft 22, etc.

In Figure 3, 18 indicates the door hinge casting by the use of which it is unnecessary in small machines, like those used on grain threshers, to use links at both ends of the doors, the torsion of the casting supporting the ends of the doors opposite to the links, and the weight of this casting at the pivot point of the links or nearer the free edges of the doors materially assists in the holding power of the open door.

The deflector shown in Figure 6 is a blade like structure fastened rigidly to shaft 22, but may be permitted to have play therewith, and having upwardly extending flanges at each end thereof 47, to form it into a chute. It will be readily understood that the blade will, as the doors are opened and closed alternately, turn under hopper 28 and direct the flow of commodity into the proper compartment.

The deflector shown in Figure 7 consists of a plate 48, with edges slightly curved 49 and 50, and with ends bent into a rectangular position to form it into a chute and to give surfaces for pivoting it to hopper 28 as at 51 and a like pivot at the other end of the hopper (not shown). This deflector is operated by a pin or roller on locking arm 23 (not shown) engaging race 52 on the deflector. With this relation of parts it will direct the flow of commodity into the compartment having its door closed and will alternate as the doors are opened and closed.

While the chute or deflector shown in Figure 1 is considered preferable under most conditions, the deflectors or chutes shown in Figures 6 and 7 may be used to advantage where the environment is not favorable for the use of the first mentioned, for instance, in some cases where this weigher is attached to an old elevator structure.

In the trip device shown in Figures 8 and 9, 53 indicates a post fastened rigidly to the partition 2, as at 54 and 55, provision is made for shaft 22 passing through the post 56, the shaft may be journaled therein, and a stop 57, is attached to the upper portion of the post in such manner as to permit to slide up and down as at 58. The lower end of the stop rests on arm 59 which is pivoted on the post structure at 60, and

a link 61 is pivotally connected to the arm at 62. The upper end of said link being adapted to connection with any convenient object stationary relative to the downward and upward movement of the container. 70 This trip is adapted to work in connection with locking lever 23 in lieu of the gravity catches 26 and 27, and adjustable gravity catches may be employed as the arms of the stop 57 (such gravity catches not 75 shown), however the stop as shown will yield upwardly to permit free passage of the locking lever to locking position. This trip may be employed where a more restricted movement of the scale beam, or container 80 is desired, or where a deeper engagement of the latch is necessary, and as it is substantially self contained with the container it is not subject to vibration.

In Figure 10, 63 indicates a grooved wheel 85 like sector to be fastened to shaft 22 by set screw 64, and cable 65 occupies the grooved section. The lower ends of the cable are attached to the doors respectively. Screw 67 holds the cable in position and also provides means for tightening the cable, as between the doors, as by pressing the cable down into the circular opening with the screw 67 will tighten the cable. It will be understood that this combination will give 90 95 the same leverage movement in relation to the doors as rocker 21, and it will also be understood that it may be used with knife edges as bearing shown in Figures 4 and 5, and it will be found desirable under some 100 condition, particularly where the conditions will permit the cables operating through the compartments and consequently through the commodity being weighed.

From the above description, it will be apparent that I have produced improvements in automatic weighers which will operate efficiently, reliably and embody the desirable features of simplicity, strength and durability and comparative inexpensiveness of 105 construction.

I desire the right to present additional claims from time to time as may be necessary to fully protect my invention.

I claim:

1. In an automatic weigher, a container having two compartments, wing pivoted doors controlling the discharge openings of said compartments respectively, said doors having upwardly extending flanges at the outer edges thereof, and hinges above the plane of the supporting surfaces thereof, a division bar between the free edges of the doors, a rocker element pivotally mounted above the plane of said doors and so connected to said doors so that as either door shall open the other door shall close, the connections to the rocker element being above the plane of the pivot mounting thereof. 115 120 125 130

2. In an automatic weigher, a container having two compartments, hinged wing doors controlling the discharge openings of said compartments respectively, said doors having upwardly extending flanges at the outer edges thereof, the hinge points of said doors placed above the plane of the commodity supporting surfaces of the doors, the lower side walls of the compartments shaped to form a depending flange overlapping the inner surfaces of the flanges at the outer edge of said doors, when the doors are closed, and a pivoted rocker element mounted above the plane of said doors with power transmitting means connected to said doors respectively and to respective sides of said element above the pivotal mounting thereof. 6. In an automatic weigher, a yieldingly elevated container having two compartments, hinged wing doors controlling the discharge openings of said compartments respectively, an upwardly extending flange at the outer edges of said doors, the hinges of said doors positioned above the plane of the commodity supporting surfaces of the doors, the lower edges of the outer side walls shaped to overlap the inner surfaces of said upwardly extending flanges at the outer edges of the doors, when the doors are closed, and a rocker element pivotally mounted above the plane of the hinges of the doors and power transmitting means connected to the respective sides of said rocker element whereby as either door shall open the other door shall close, the connections of said means to said rocker element positioned above the pivotal mounting of said rocker element, and a latch mechanism to lock and unlock the doors. 7. In an automatic weigher, a yieldingly elevated container having two compartments, wing hinged doors controlling the discharge openings of said compartments, respectively, a rocker element mounted pivotally above the plane of the doors and means connecting the respective sides thereof to the doors respectively, the connections of said means to said rocker element being above the pivotal mounting thereof. 8. In an automatic weigher, a yieldingly elevated container having two compartments, wing hinged doors controlling the discharge openings of said compartments, respectively, a rocker element pivotally mounted above the plane of the hinges of said doors with connections to said doors whereby as either door shall open the other shall close, the connections to said rocker element positioned above the pivot point thereof and laterally at similar distances from the vertical plane of the pivotal mounting of said rocker element when in central position, and employing the operative power of the opening door, under the gravitational force of the weighed commodity, irrespective of the downward movement of the container, in closing the other door and in other operable elements. 9. In an automatic weigher, a two compartment container, a pair of pivoted wing doors controlling the discharge openings of said compartments respectively, a pivotally mounted rocker element, links pivotally connected to said doors and to respective sides of said rocker element at points above the pivotal mounting thereof, a locking element connected to said rocker element and a pair of gravity catches adapted to engage with respective sides of said locking element to alternately lock and unlock said doors respectively. 10. In an automatic weigher, a two compartment container, a pair of pivoted doors controlling the discharge openings of said
- 5 10 15 20 25 30 35 40 45 50 55 60 65 70 75 80 85 90 95 100 105 110 115 120 125 130

compartments respectively, a pivoted rocker element, links connecting said doors respectively to respective sides of said rocker element at points above the pivot thereof, means for locking said rocker element in alternate reverse positions and thereby alternately lock and unlock the said doors, and a hopper like chute for feeding com-

modity to said container and a pivoted element turning under the discharge opening of said chute to alternately deflect the commodity into said compartments alternately, and pivoted means connecting said deflector with said rocker element to operate the deflector.

JAMES B. VAN DEREN.
